UNITED STATES PATENT OFFICE.

LOUIS R. SCHMERTZ, OF JEANNETTE, PENNSYLVANIA, ASSIGNOR TO WINDOW GLASS MACHINE COMPANY, OF PITTSBURGH, PENNSYLVANIA, A CORPORATION OF NEW JERSEY.

METHOD AND APPARATUS FOR FLATTENING AND ANNEALING SHEET GLASS.

Application filed August 5, 1924. Serial No. 730,204.

To all whom it may concern:

Be it known that I, LOUIS R. SCHMERTZ, a citizen of the United States, residing at Jeannette, county of Westmoreland, State 5 of Pennsylvania, have invented a new and useful Improvement in Methods and Apparatus for Flattening and Annealing Sheet Glass, of which the following is a full, clear, and exact description.

10 This invention relates to the making of flat sheet glass and is particularly applicable to the flattening oven and connected leer tunnel generally employed in conjunction with the cylinder process of making window 15 glass. In the copending application of Lawrence A. Gessner, Serial No. 672,530, filed Nov. 3, 1923, there is shown a leer tunnel wherein compensation is made for the natural shrinkage of the hot gases as they 20 pass from the flattening oven through the leer tunnel. Such an apparatus prevents the ingress of cold air to any substantial distance from the delivery end of the leer tunnel and provides a smooth laminar flow 25 of the products of combustion from the flattening oven through the leer tunnel. The cooling effect is thereby so controlled as to substantially equalize the rate of heat loss from the two faces of the glass sheets and 30 the glass does not become warped or bowed, but is delivered substantially flat.

In the co-pending application of John Hartzell, Serial No. 693,249, filed Feb. 16, 1924, there is shown a form of leer tunnel 35 for achieving the same result wherein dampers are employed to divert a portion of the heated gases from one of the gaseous streams to the other, thus off-setting the natural tendency of the hotter portions of the 40 gases to rise to the upper portions of the leer.

I have found, however, that when a leer constructed according to either of such inventions is used there is a marked tendency 45 toward an increased temperature in the so-called piling oven. This is probably due to the restriction on the flow of hot gases through the leer tunnel as compared with leers previously used, so that the principal 50 outlet for the products of combustion is choked off to a certain extent.

As a result of this condition the flattening stones are increased in temperature and when unflattened glass is placed thereon

the stones are apt to "burn" or mark the 55 lower surfaces of the sheets. It will be understood that in a leer of this character the flattening stones are carried on a large wheel so that a stone is first in the flattening oven, where the heat is generally applied and 60 where the operation of flattening is performed, after which the wheel is rotated a sufficient distance to carry the stone with a sheet of flattened glass thereon into a so-called dummy oven of lower temperature, 65 and then through the so-called cooling oven to the piling oven, where the workman lifts the now partially cooled sheet off the stone onto the leer rods. It is necessary to raise the temperature of the glass in the flattening oven to above the annealing point of the glass in order to flatten the same and the oven will, of course, be hotter than the 70 glass which it heats, but it is highly desirable to keep the stones relatively cool and supply the requisite heat to the glass from above, since this avoids marking of the glass by the stones, as is well known to those skilled in the flattening art.

Heretofore, this desirable condition of the 80 flattening stones has been easily maintained but, as above stated, the regulation of the flow of gases through the flattening oven in order to prevent warping of the glass during cooling results in an increased temperature 85 on the piling side of the flattening oven, with a consequent loss of opportunity for the stones to cool off when they are outside the flattening oven proper.

I have found that the burning of the 90 glass may be overcome by preheating the glass, preferably to very near the annealing temperature. When this is done the glass may be flattened very quickly and the work 95 of the flattener is considerably reduced since the unflattened glass "lies down" almost immediately and requires only a small amount of rubbing. The time required for the actual flattening operation being thus cut down, a material increase in the production 100 of the oven may be attained, and with this increased speed I have found that the tendency of the stones to burn the glass is overcome.

The preheating of the glass cylinders or 105 shawls is preferably accomplished at a plurality of stations as the unflattened glass may be more uniformly heated in this man-

ner and sufficient time is available to pre-heat the glass as much as desired even at the highest oven speeds.

5 In the accompanying drawings illustrating the present preferred embodiment of my invention,

Figure 1 is a horizontal section taken on the line I—I of Figure 2 and showing a flattening oven embodying my invention;

10 Figure 2 is a longitudinal vertical section on the line II—II of Figure 1;

Figure 3 is a view to enlarged scale of a portion of Figure 1;

15 Figure 4 is a vertical section on the line IV—IV of Figure 3;

Figure 5 is a view similar to Figure 4 but showing another position of the apparatus, and

20 Figure 6 is a vertical section on the line VI—VI of Figure 4.

In the illustrated embodiment of the invention there is shown a flattening oven indicated generally by the reference character 2 and a connected leer tunnel 3. Leer 25 rods 4 are provided for passing glass in sheet form through the leer and in order to insure the flatness of the product the leer 3 may be provided with a sloping bottom 5, as disclosed and claimed in the above mentioned Gessner application, and also with adjustable dampers 6 as disclosed and claimed in the above mentioned application of John Hartzell.

35 The flattening oven is provided with a wheel 7 carrying flattening stones 8 adapted to lie, successively, in a flattening oven 9, a dummy oven 10, a cooling oven 11 and a piling oven 12 as the wheel 7 is rotated. Heat is supplied in any desired manner, as 40 by burners 13. Heating gases from these burners maintain the flattening oven 9 at the desired temperature and then pass under suspended arches 14 which partially separate the flattening oven, the dummy oven, the cooling oven and the piling oven. After passing under these arches a large portion of the gases travel down the leer tunnel 3 and out the delivery end 15.

45 As above stated, the provision of the sloping floor 5 and the dampers 6, both of which are exceedingly desirable in the production of unwarped glass, results in a choking off of the flow of gases through the tunnels 15 so that the heating gases must find other outlets. This results in an increased temperature in the piling oven, cooling oven and the dummy oven, and as a result the stones 8 increase in temperature. With an oven operated in this manner burning of 55 the glass is likely to result unless great care is taken.

60 In accordance with my invention, however, the stick-hole 16 is provided with means for supporting the unflattened glass in position to be heated by the gases flowing

from the oven out of the stick-hole. The apparatus preferably employed comprises a traveling frame 17 having a plurality of sets of supports 18 and 18^a thereon for holding the shawls or cylinders and a lifting frame 19 having corresponding supports 20 and 20^a thereon for holding the glass during the backward movement of the traveling frame 17.

65 In operation, a shawl is placed on the supports 20 and the lifting frame is moved to its upper position, as illustrated in Figure 5. This upward movement is accomplished by a rod 21 and operating levers 22. The levers 22 are connected by downwardly 80 extending rods 23 to cross bars 24, which carry the lifting frame 19. The lower end of the rod 21 is provided with a hook portion 25 adapted to engage notches 26 for holding the lifting frame in raised or low- 85 ered position.

With the frame 19 in raised position the traveling frame 17, which is carried by rollers 27, is pulled outwardly by means of a handle 28 until the supports 18 lie adjacent the supports 20. The lifting frame 19 is then lowered, transferring the shawl from the supports 20 to the supports 18, and the traveling frame is shoved inwardly. 90

At the innermost position of the frame 17 the supports 18 lie adjacent the supports 20^a so that the next time the frame 19 is lifted the shawl is transferred from the supports 18 to the supports 20^a and when the traveling frame is drawn out and the 100 lifting frame again lowered the shawl is transferred to the supports 18^a. On the next inward movement of the traveling frame 17 there will be two shawls in the stick-hole, occupying the positions shown in 105 Figure 4 and thereafter there will always be two shawls in process of heating. The leading shawl is lifted off the supports 18^a by the flattener, who transfers it to the flattening stone in the flattening oven 9. As 110 soon as this shawl has been removed a workman places another shawl on the support 20 and operates the apparatus as above described to advance the shawl already in the stick-hole from its first position to the position just vacated by the shawl now being flattened, the operation continuing as long as the oven is worked. A vertically adjustable cover 28, provided with a counter-weight 29, is provided for the stick-hole. 115

120 By reason of the preheating the glass is brought up very close to a suitable flattening temperature before it is placed on the flattening stone, the heating being accomplished in the stick-hole 16. The work of 125 the flattener is thereby materially reduced since the shawl lies down readily and requires only a small amount of rubbing to complete the flattening operation. The production of the oven may be thus materially 130

increased and because of the increased speed of the wheel the glass is handled without its being burned or marred by the hotter condition of the flattening stone.

5 I thus provide for flattening and annealing glass by preheating the unflattened glass to compensate for the increased temperature of the flattening stones induced by the regulation of the gaseous flow from the 10 flattening oven through the leer. With my invention it is possible to produce flat glass and, at the same time, to materially increase the quality and quantity of the product.

It will be understood that the heat may 15 be supplied at other places than in the particular portion of the apparatus where the flattening operation is carried out, and I use the term "flattening oven" in its broader sense in the appended claims to signify not 20 only the flattening oven proper, but also the dummy-oven, the cooling oven, and the piling oven.

While I have shown a preferred form of my invention, it will be understood that it 25 is not limited thereto, but may be otherwise embodied within the scope of the following claims.

I claim:

1. In the method of making flat sheet 30 glass, the steps consisting in supplying unflattened glass to a flattening oven, flattening the glass therein, passing it from the oven through a leer to anneal and cool the glass, supplying heating gases to the flattening oven, passing heating gases from the flattening oven through the leer in streams above and below the glass, so regulating the relative rate of flow of the gases above and below the glass as to equalize the rate of cooling from the two faces of the glass therein, and preheating to near flattening temperature 35 the unflattened glass supplied to the flattening oven to reduce the time of contact of the glass with the surfaces contacting therewith in the flattening oven and thus compensate for the increased temperature 40 of such surfaces induced by the regulation of the gaseous flow from the flattening oven to the leer.

2. In the method of making flat sheet 45 glass, the steps consisting in supplying unflattened glass to a flattening oven, flattening the glass therein, passing it from the oven through a leer to anneal and cool the

glass, supplying heating gases to the flattening oven, passing heating gases from the flattening oven through the leer in streams above and below the glass, so regulating the relative rate of flow of the gases above and below the glass as to equalize the rate of cooling from the two faces of the glass therein, and preheating in a plurality of stages the unflattened glass supplied to the flattening oven to compensate for the increased temperature of the surfaces contacting with the glass in the flattening oven 60 induced by the regulation of the gaseous flow from the flattening oven to the leer.

3. In the method of making flat sheet 65 glass, the steps consisting in supplying unflattened glass to a flattening oven, flattening the glass therein, passing it from the oven through a leer to anneal and cool the glass, supplying heating gases to the flattening oven, passing heating gases from the flattening oven through the leer in streams 70 above and below the glass, so regulating the relative rate of flow of the gases above and below the glass as to equalize the rate of cooling from the two faces of the glass therein, and preheating to near flattening temperature 75 the unflattened glass supplied to the flattening oven to reduce the time of contact of the glass with the surfaces contacting therewith in the flattening oven and thus compensate for the increased temperature 80 of such surfaces induced by the regulation of the gaseous flow from the flattening oven to the leer.

4. Apparatus for making flat sheet glass, including a flattening oven and connected 85 leer tunnel, the tunnel being of restricted area and adapted for the passage of gaseous fluid from the flattening oven through the leer, and means for preheating the unflattened glass supplied to the flattening oven. 90

5. Apparatus for making flat sheet glass, including a flattening oven and connected 95 leer tunnel, the tunnel being of restricted area and adapted for the passage of gaseous fluid from the flattening oven through the leer, and means for preheating in a plurality of stages the unflattened glass supplied to the flattening oven. 100

In testimony whereof I have hereunto set my hand.

LOUIS R. SCHMERTZ.
